US00D572267S

(12) **United States Design Patent**
Andre et al.

(10) **Patent No.:** US D572,267 S
(45) **Date of Patent:** ** Jul. 1, 2008

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/283,604**

(22) Filed: **Aug. 17, 2007**

Related U.S. Application Data

(63) Continuation of application No. 29/278,280, filed on Mar. 23, 2007, now abandoned, which is a continuation of application No. 29/237,229, filed on Aug. 24, 2005, now Pat. No. Des. 541,298.

(51) **LOC (8) Cl.** **14-03**

(57) **CLAIM**

We claim the ornamental design for a media device, substantially as shown and described.

DESCRIPTION

FIG. 1 is a perspective view of a media device in accordance with the present design.

FIG. 2 is a front view for the media device.

FIG. 3 is a rear view for the media device.

FIG. 4 is a bottom view for the media device.

FIG. 5 is a top view for the media device.

FIG. 6 is a right side view for the media device; and,

FIG. 7 is a left side view for the media device.

The broken lines are for illustrative purpose only and form no part of the claimed design.

1 Claim, 3 Drawing Sheets
